UNITED STATES PATENT OFFICE.

SAMUEL A. BOYD, OF SASAKWA, OKLAHOMA.

RAIL-JOINT.

1,299,545.

Specification of Letters Patent.

Patented Apr. 8, 1919.

Application filed November 21, 1918. Serial No. 263,575.

To all whom it may concern:

Be it known that I, SAMUEL A. BOYD, a citizen of the United States, residing at Sasakwa, in the county of Seminole and

5 State of Oklahoma, have invented certain new and useful Improvements in Rail-Joints, of which the following is a specification.

This invention relates to rail joints and has for its object to provide a comparatively 10 simple and thoroughly efficient device of this character, by means of which the confronting ends of rails in a line of track may be quickly and conveniently coupled and said rails securely held in longitudinal alignment under all conditions of service.

A further object of the invention is to provide a safety joint, the rail ends of which are provided with interlocking parts disposed beneath the rails and so constructed as 20 to prevent sagging of the abutting ends thereof, thereby obviating the necessity of tamping up low joints and effectually preventing pounding and mutilation of the rail ends incident to the travel of cars and other 25 rolling stock thereover.

The invention further aims to provide a rail joint, the rail ends of which are interchangeable so that when one side of any rail becomes worn or otherwise impaired from 30 constant use the position of said rail may be reversed whereby to present a fresh track surface to the car wheels.

The invention further contemplates a joint which may be applied to the standard 35 type of rail without necessitating any structural changes therein and in which wear and strains on the angle bars and securing bolts are reduced to a minimum.

A still further object is generally to improve 40 this class of devices so as to increase their utility, durability and efficiency.

Figure 1 is a perspective view of a portion of a railroad track provided with a rail joint constructed in accordance with the 45 present invention;

Fig. 2 is a detail side elevation of one of the joints;

Fig. 3 is a bottom plan view;

Fig. 4 is a detail perspective view of abutting ends of mating sections showing the construction of the locking device;

Fig. 5 is a detail transverse sectional view.

The improved joint forming the subject-matter of the present invention is principally designed for connecting the confronting ends of railway rails and by way

of illustration is shown applied to a section of track in which 5 designates the rails, 6 the abutting ends thereof and 7 the cross-ties to which the rails are secured. 60

Secured to or formed integral with the base flanges 8 of the rails at the abutting ends thereof are depending enlargements indicated as a whole at 9, said enlargements being provided with interlocking parts, the 65 construction of which will be more fully explained hereinafter. The enlargements 9 register with each other when the rails are assembled and serve to reinforce and brace the rails at the abutting ends thereof so as 70 to effectually prevent sagging of the rail ends and pounding or mutilation of said ends incident to the passage of cars and other rolling stock thereover. When the rails are assembled, the extensions 9 fit between and bear against the adjacent cross-ties 7 and in which position they are 75 securely held by means of spikes or other fastening devices 10 driven into the cross-ties and engaging suitable angle bars or 80 fish plates 11, as shown. The angle bars 11 are provided with elongated openings 12 for the passage of securing bolts 13 which latter extend through the webs of the rails in the usual manner so as to permit expansion and 85 contraction of the rails due to temperature changes.

The rear end of the enlargement 9 of each rail preferably extends the entire width of the base flange thereof and is cut away to 90 form a horizontally disposed lip 14 also preferably extending the entire width of the base flange of the rail, as shown. Spaced from the lip 14 is a substantially L-shaped extension 15, the long arm of which is preferably substantially one-half the width of the base flange of the rail, while the short arm of the extension extends substantially the entire width of the base flange of the rail and has its under side cut away to form 100 a transverse locking lip 16 adapted to fit within the groove formed by the locking lip 14 of a mating rail end when the rails are assembled. The extension 15 is spaced from the adjacent lip 14 to produce an intermediate passage 17 which accommodates the short arm 18 of the adjacent L-shaped extension so that when the rails are assembled the inner faces of the extensions 15 will abut and thus prevent lateral displacement of the 110 rail ends. It will here be noted that the extensions 15 project longitudinally beyond

the abutting ends 6 of the rails so that when the rails are assembled the extension 15 of one rail will overlap the base flange of the adjacent rail and thus form a firm anchorage and reinforcement for the abutting ends of said rails. The recesses 17 open through the opposite longitudinal edges of the rails so that the rails may be readily assembled by causing the lips 16 to register with the recesses formed by the lips 14 and then pressing laterally on the rail ends until the adjacent faces of the extensions 15 abut and in which position the rails will be securely held in longitudinal alinement. It will, of course, be understood that there will be sufficient play between the extensions and the lips 14 to allow for expansion and contraction of the rails under temperature changes. The locking members are identical in construction with the exception that the extension 15 at one end of each rail is arranged on one side of the longitudinal axis of the rail, whereas the extension on the opposite end of the rail is disposed on the other side of the other longitudinal axis of the rail. By making the locking members in this manner the rail ends are rendered interchangeable so that should the tread surface of a rail become worn or otherwise impaired from constant use the position of the rail may be readily reversed thereby to present a new tread surface to the car wheels. It will, furthermore, be noted that the locking members comprising my improved joint are disposed entirely beneath the base flanges of the rails so as to render it unnecessary to cut or otherwise weaken the vertical webs or tread faces of the rails and permitting the device to be used in connection with the standard type of rail without necessitating any structural changes therein, it being merely necessary to weld or otherwise secure the interlocking parts on the base flanges of the rails as will be readily understood. Moreover, as the interlocking members comprising my improved joint are disposed beneath the rails at the abutting ends thereof, strain and wear on the bolts and angle bars is reduced to a minimum.

50 A joint constructed in accordance with the present invention may be quickly coupled, and effectually prevents sagging or low joints at the abutting ends of the rails with consequent pounding and damage to both the rail ends and wheels of the rolling stock.

Having thus described my invention, what is claimed as new is:

1. A rail joint including coacting rails having enlargements depending from the base flanges thereof at their abutting ends and provided with interengaging parts for locking said rails against longitudinal separation.
2. A rail joint including coacting rails having enlargements depending from the

base flanges thereof at their abutting ends and provided with interlocking parts, each enlargement being provided with a flat side face adapted to bear against the adjacent side face of a cross-tie.

70

3. A rail chair including coacting rails having enlargements depending from the base flanges thereof at their abutting ends and provided with interlocking parts, the enlargements when coupled being adapted to fit between a pair of cross-ties, angle bars bearing against the webs of the rails and spanning the junction of said rails, and fastening devices engaging the angle bars and adapted to enter said cross-ties.

80

4. A rail joint including coacting rails each having an enlargement depending from the base flange thereof at their abutting ends, the enlargement of one rail end being provided with an L-shaped extension adapted to engage a transverse lip formed on the extension of a mating rail end.

85

5. A rail joint including coacting rails having enlargements depending from the base flanges thereof at their abutting ends, each enlargement being provided with a transverse lip, and a substantially L-shaped extension spaced from said lip and projecting beyond the adjacent end of the rail.

90

6. A rail joint including coacting rails having enlargements depending from the base flanges thereof at their abutting ends, the enlargement of each rail being provided with a transverse lip extending the entire width of the base flange of the rail, and a substantially L-shaped extension spaced from said lip and projecting longitudinally beyond the adjacent end of the rail, the extension being substantially one-half the width of the base flange of the rail and the projecting end of the extension being provided with a transverse lip adapted to engage the transverse lip of a mating rail when said rails are assembled.

95

7. A rail joint including coacting rails having enlargements depending from the base flanges thereof at their abutting ends, each enlargement being provided with a transversely disposed overhanging lip spaced from the base flange of the rail and extending the entire width thereof, and a substantially L-shaped extension spaced from the transverse lip and projecting beyond the adjacent end of the rail, the short arm of the L-shaped extension being reduced to form a transverse lip adapted to fit between the overhanging transverse lip and base flange of a mating rail when said rails are assembled.

100

8. A rail joint including coacting rails having enlargements depending from the base flanges thereof at their abutting ends, the enlargement of each rail end being provided with a transverse lip extending the entire width of the base flange of the rail.

130

and spaced therefrom and a substantially L-shaped extension, the long arm of which is spaced from the lip and is of substantially one-half the width of the base flange of the rail, the short arm of the extension projecting beyond the adjacent end of the rail and being of a width substantially equal to the width of the base flange of the rail and having its lower face cut away to form a transversely disposed lip adapted to enter the space between the transverse lip and base flange of the mating rail when the rail ends are assembled with the adjacent faces of the long arms of the extensions abutting to prevent lateral displacement of the rails.

9. A rail joint including coacting rails having enlargements depending from the base flanges thereof at their abutting ends and provided with interengaging parts for locking the rails against longitudinal separation said rail ends being interchangeable.

10. A rail joint including coacting rails having enlargements depending from the base flanges thereof at their abutting ends and provided with interlocking parts, the rails being interchangeable and the locking members separable laterally to permit uncoupling of the rails.

In testimony whereof I affix my signature.

SAMUEL A. BOYD. [L. s.]
